By Chas. C. Utterman,

UNITED STATES PATENT OFFICE.

CHARLES D. WRIGHT, OF CHICAGO, ILLINOIS.

ELECTRIC IGNITER.

SPECIFICATION forming part of Letters Patent No. 666,618, dated January 22, 1901.

Application filed May 29, 1899. Serial No. 718,780. (No model.)

To all whom it may concern:

Be it known that I, CHARLES D. WRIGHT, a citizen of the United States, residing at Chicago, in the county of Cook and State of Illinois, have invented certain new and useful Improvements in Electric Igniters, of which the following is a specification.

This invention relates to improvements in devices to be employed for igniting gases, and 10 while it is more especially intended to be used in connection with stoves in which gas or gasoline is used as fuel, yet it may be employed for igniting gases used for other purposes; and it consists in certain peculiarities of the 15 construction, novel arrangement, and operation of the various parts thereof, as will be hereinafter more fully set forth and specifically claimed.

One object of my invention is to provide a 20 simple and inexpensive igniter for gas and other ignitable substances which shall be of such a construction and nature that an electric spark may be produced at the desired time and point, thus dispensing with the use 25 of matches or tapers, the unburned portions of which are frequently thrown aside while still burning and often cause accidental fires and explosions.

Another object of my invention is to so construct the handpiece of the igniter that it 30 will not become short-circuited when laid upon a metallic surface.

Still another object of my invention is to so 35 construct it that it may be readily attached to the supply-pipe of the stove in such a position that it will be entirely out of the way and yet always accessible.

In order to enable others skilled in the art 40 to which my invention pertains to make and use the same, I will now proceed to describe it, referring to the accompanying drawings, in which—

Figure 1 is a perspective view of a gas-stove with my igniter attached thereto. Fig. 45 2 is a perspective view of the handpiece of the igniter, showing by dotted lines the position which a portion thereof will assume when the spark shall have been produced. Fig. 3 is a central sectional view of the battery and coil casing; and Fig. 4 is a side or 50 detached view of a portion of the handpiece,

showing the relative positions of the contacting points.

Similar letters refer to like parts throughout the different views of the drawings. 55

A represents the casing for the battery-cells B and B' and sparking coil C, which casing is preferably tubular, as shown in the drawings, and may be provided with clamps a to encircle the gas or gasoline supply pipe 60 A' of the stove. Secured to one end of the casing A is a metal cap A², which has a central projection a' to rest against one end of the contact-post b of the battery B', the other end of which post rests against the adjacent end of the post b of the battery B, the other end of the post b of the battery B resting against the adjacent end of the post c of the sparking coil C, the other end of said 65 sparking-coil post resting against a plate d, 70 insulated from the metal cap A², secured on the other end of the casing.

Passing through the cap A² and insulated therefrom is a conductor D, one end of which contacts with the plate d, and the other end 75 thereof is secured to the handpiece E, as shown in Fig. 2 of the drawings. Connected at one of its ends to the cap A² is another conductor D', whose other end is electrically connected to a metal spring e, which is secured 80 to one end of the handpiece E and insulated therefrom. (See Fig. 2.)

The handpiece E is made of a piece of wire bent back upon itself to form a spring and having near one of its ends a U-shaped loop 85 E' for the reception and operation of the other end of the handpiece, which is provided with a piece e, preferably in the form of a spiral spring, to contact with the arm e' of the handpiece, which arm projects crosswise of the 90 loop E', but at some distance therefrom, as is clearly shown in Figs. 2 and 4 of the drawings. The arm e' is of sufficient length and so bent as to prevent it and the piece e contacting at the same time with the metal surface, such as the top of the stove, on which 95 the handpiece may be placed, thus preventing short-circuiting, which would occur if a piece of metal united the piece e and the arm e' or other portion of the handpiece. 100

From the foregoing and by reference to the drawings it will be seen and clearly under-

stood that by pressing the portions of the handpiece toward each other, so that the piece *e* will contact with the arm *e'*, a spark will be produced, the conductor *D* being connected to one of the poles of the batteries, while the conductor *D'*, through the metallic caps *A²* *A³* and casing *A*, is connected to the other pole.

It is apparent that the batteries must be insulated from the casing, and this may be done by providing the interior of the casing or the exterior of the batteries with suitable insulating material, or they may be insulated in any other desired manner.

Having thus fully described my invention, what I claim as new, and desire to secure by Letters Patent, is—

1. In an electric igniter, a handpiece comprising a continuous piece bent to form a

spring, and having near one of its ends a loop provided with a contact-arm, and its other end passing through said loop and provided with a contact-point, substantially as described.

2. In an electric igniter, a handpiece comprising a continuous piece bent to form a spring, and having near one of its ends a transverse loop and provided with a contact-arm located crosswise said loop, and its other end passing through said loop and provided with a yielding contact-point, substantially as described.

CHARLES D. WRIGHT.
